UNITED STATES PATENT OFFICE.

LIGE H. KIRKPATRICK, OF LAWTON, OKLAHOMA.

FUEL MIXER FOR INTERNAL-COMBUSTION ENGINES.

Application filed January 24, 1925. Serial No. 4,604.

To all whom it may concern:

Be it known that I, LIGE H. KIRKPATRICK, a citizen of the United States, residing at Lawton, in the county of Comanche and 5 State of Oklahoma, have invented a new and useful Fuel Mixer for Internal-Combustion Engines, of which the following is a specification.

This invention relates to a fuel mixer for 10 internal combustion engines designed to be located in the opening between the intake manifold and the engine intake.

The object of the invention is to provide 15 a simple and efficient device of this character in which the current of fuel is mechanically regulated and broken into particles of vapor at the point nearest the compression and explosion and by means of which the fuel is effectively vaporized before entering the engine cylinder.

With the foregoing and other objects in view which will appear as the description proceeds, the invention resides in the combination and arrangement of parts and in the 25 details of construction hereinafter described and claimed, it being understood that changes in the precise embodiment of the invention herein disclosed may be made within the scope of what is claimed without 30 departing from the spirit of the invention.

In the accompanying drawings:—

Figure 1 represents a front elevation of the device constituting this invention;

Fig. 2 is a transverse vertical section there- 35 of; and

Fig. 3 is an enlarged detail of the inter- laced filaments constituting the invention.

The fuel mixer constituting this invention 40 comprises a plurality of brushes or bunches of filaments shown at 1 and supported by any suitable means whereby they may be located at the desired point for breaking up the fuel passing through them. These filaments are fixed at one end and free at the 45 other and are made short enough so that while they intercept all gas by their interlacing they make no fixed or bag-like construction to catch and hold dirt or solid particles of any kind which would cause a hindrance to the passage of the gasoline or other fuel. As here shown the support is in the form of a gasket ring or gland 10, the flange 50 11 of which is designed to be clamped between the intake manifold and the engine. 55 These brushes or bunches 1 may be made of any suitable material such as brass, copper,

aluminum, steel or other metal and may contain any desired number of filaments, strands or the like. These filaments may be of any shape desired. Any number of brushes 1 60 may be set in the gland, eight being shown in Fig. 1 and which are arranged in peripheral or circumferential alinement although not necessarily so. If desired these brushes may be arranged in series as shown 65 in Fig. 2.

The filaments or wires 2 of the brushes are so interlaced as to regulate the flow of the fuel and increase the vaporization there- 70 of while the ends of said filaments being free prevents clogging or stopping of the current.

While these filaments or brushes are shown 75 mounted on a gasket ring any suitable supporting base or means may be provided. The intertwining or interlacing of the filaments provides an extended area to facilitate evaporation and volatilization of the fuel. These filaments completely cover the passage or conduits and while interlacing at the 80 same time have free ends thus operating to thoroughly nebulize the fuel. It is well known that in the swift flow of any liquid or gas through a pipe the tendency of the liquid is toward the center of the pipe for the reason that at that point there is the 85 least resistance of gravitation, cohesion, adhesion or temporary attraction and therefore any solid or gasified fuel will be drawn to that point in the pipe or conduit and more easily drawn into the engine in an ungassed condition. This objectionable feature is 90 overcome in the device herein described.

This attachment it will be seen is extremely simple and may be applied by simply detaching the manifold from the engine 95 and inserting the gasket ring containing the brushes between the manifold and the engine and clamping it again in place. This location of the atomizer within an inch or less of the combustion chamber avoids all 100 possibility of recondensation after vaporization and before ignition in the combustion chamber. This is a distinct advantage especially in cold weather.

I claim:—

1. A device of the class described comprising a gasket ring having a plurality of brushes of metal strands arranged around the perimeter on the inner face thereof, the strands of said brushes extending toward 110 each other and being intertwined and their ends left free.

2. In a device of the class described, a supporting ring adapted to be positioned within an intake manifold, a plurality of brushes formed of metal strands, secured to the ring and disposed in spaced relation with each other, and the bristles of the brushes being intertwined.
3. In a device of the class described, a supporting member adapted to be positioned in an intake manifold, a plurality of brushes

formed of wire material, the bristles of the brushes extending towards the center of the supporting member, and the bristles of the brushes being interwoven to restrict the passage of fuel through the manifold.

In testimony that I claim the foregoing as my own, I have hereto affixed my signature.

LIGE H. KIRKPATRICK.
